UNITED STATES PATENT OFFICE.

JOHN J. EVERSON, OF NEWTON, MASSACHUSETTS.

ARTIFICIAL HAND.

1,416,180.

Specification of Letters Patent. Patented May 16, 1922.

Application filed June 10, 1919. Serial No. 303,045.

To all whom it may concern:

Be it known that I, JOHN J. EVERSON, a citizen of the United States, and a resident of Newton, Massachusetts, (whose post-office address is Cabot Street, Newton, Massachusetts,) have invented an Improvement in Artificial Hands, of which the following description, in connection with the accompanying drawings, is a specification, like letters on

10 the drawings representing like parts.

This invention relates to artificial limbs and particularly to artificial hands and arms. The invention is especially concerned with artificial hands of the general construction 15 shown in my prior application Serial No. 247,944 filed August 2, 1918. This construction of artificial hand has proved in practice to be a substantial advance in this art and the present invention aims to further 20 improve my earlier construction.

It is a particular object of the invention to devise an artificial hand of the character above mentioned which can be economically manufactured and will possess even greater 25 utility than my former construction and to devise a novel connection between hand and forearm with the aid of which the hand can be quickly and easily adjusted into different positions.

30 To these ends the invention involves novel features of construction of the hand itself designed to improve it from an assembling and manufacturing standpoint, a novel mounting for the thumb, and a novel connection between the hand and forearm. These and other features of the invention 35 which will hereinafter appear will be readily understood from the following description when read in connection with the accompanying drawings, in which—

Figure 1 is a rear view of a hand partly broken away to illustrate the interior constructions;

Fig. 2 is a front elevation of a skeleton of 45 a hand;

Fig. 3 is a side elevation of the parts shown in Fig. 2;

Fig. 4 is a rear elevation of the parts shown in Fig. 2; and

50 Fig. 5 is a plan view of the base that supports the other parts of the hand.

The hand construction illustrated is preferably of the general character illustrated in my prior application above designated and 55 also in my pending application Serial No. 182,440 filed July 24, 1917. As will be seen from the drawings, the fingers 2 and thumb

3 are each provided with a resilient frame member which stiffens the fingers and holds them substantially in the desired position, 60 while still enabling them to be bent or to yield away from their normal positions to grasp an article. These frame members preferably consists of a relatively stiff, heavy, spring wire, the frame members for 65 the fingers being designated at 4 and that for the thumb at 5. A covering of yielding material, preferably heavy wool felt, encloses the frame members and is shaped to simulate a hand with thumb and fingers. 70 The felt preferably is partly molded to form the fingers and thumb and the edges are abutted together and sewed, the seams preferably being made between the fingers so that they will be partially concealed. The palm portion 75 of the hand includes a coiled spring 6 extending longitudinally of the hand and arranged to yield toward the back of the hand so that it cooperates with the fingers to enable the hand better to grip an article. 80

The construction so far described is very similar to that disclosed in my application Serial No. 247,944, above designated. In the present construction, however, a very different arrangement is employed for securing the 85 wire members 4, 5 and coiled spring 6 in their operative positions. In the present arrangement these parts are all anchored in a base piece 7 which may conveniently consist of an aluminum casting having holes, 90 indicated at 8, drilled therethrough from side to side to receive the ends of the frame members 4; another hole 9 drilled parallel to the holes 8 to receive the end of the coiled spring 6, and a hole 10 drilled longitudinally 95 therethrough from end to end to receive the thumb frame member 5. The holes 8 are arranged in pairs, each pair merging into a recess 11, Figs. 4 and 5, having high walls which serve to support the finger 100 frame members against lateral movement. The ends of the finger frame members 4 are forced through the holes 8 and the tips are turned over slightly to prevent them from being withdrawn, while the ends of the frame members 5 and coiled spring 6 are simply inserted in their respective holes 9 and 10, the covering for the hand operating to secure these parts against accidental removal. Since the hole 10 extends through the base 110 piece 7 from one end to the other, the thumb frame member 5 may be inserted in either end of this hole and, consequently, the same base and wire reinforcements can be used

for either a right or left hand. The finger frame members are substantially alike, differing only in minor bends and angles of deflection, and the same thumb frame member is used for either a right or left hand, it being merely necessary to insert it in one end or the other of the base piece 7, depending upon whether the hand is to be a right or left. The upper wall of the hole 10 is 10 broken away at each end for a ways to provide a short slot having shoulders 12, as indicated in Fig. 3, which extend back substantially to the point 13, Fig. 5. These shoulders allow the thumb 4 to have a limited 15 swinging movement back and forth about the axis of the hole 10 in a plane transverse to the plane of the palm of the hand and thus facilitate the adjustment of the thumb to cooperate with the other fingers in holding 20 articles of different sizes. This swinging movement obviously is yieldingly resisted by the covering for the hand. Preferably the fingers are tensioned or biased toward each other and the thumb is tensioned toward 25 the first finger so that small articles can be forced between the fingers, or between the thumb and the first finger, and held thereby. In order to limit the extent to which the fingers can be forced apart the outside finger 30 frame members 4 may be bent slightly, as shown in Figs. 2 and 4, to receive a light binding wire 14.

It will readily be understood that the construction above described is very economical 35 to manufacture, particularly since the same parts are used for both a right and left hand, the assembling operations being greatly facilitated by the peculiar arrangement provided for securing the frame members in 40 position.

The forearm 15 may be of any suitable or convenient construction and in order to secure the forearm and hand together in a manner that will permit the angular adjustment of the hand with reference to the forearm, or the removal of the hand from the forearm, the base 7 is provided with a shank 16, preferably of cylindrical form but centrally reduced or grooved circumferentially. 45 The forearm has mounted therein a tapered draw bolt 17 positioned to engage the groove in the shank 16 and arranged to be drawn into firm clamping engagement with the shank by a thumb screw 18 threaded on to 50 the end portion of the draw bolt where it projects at one side of the forearm. It is evident that when the thumb screw 18 is loosened the draw bolt 17 will be slackened thus permitting the hand to be turned about 55 the axis of the shank 16 into any desired position of adjustment, and that the hand can then be clamped securely in this position by turning up the thumb nut 18. This arrangement thus provides a very simple and 60 reliable means that may be conveniently op-

erated by the wearer of the limb to adjust the hand and secure it in adjusted position.

The operation of my improved device is as follows: the resilient fingers and thumbs are securely anchored in position in the base 70 block 7, as shown in Figs. 2, 3 and 4, covered with felt and leather to simulate a gloved hand, and the shank 16 inserted in a suitable socket in the forearm 15 and retained therein by the locking member 17. The pressure of 75 the member 17 on the shank 16 may be adjusted by the thumb nut 18, allowing said hand member to rotate freely with respect to the forearm or preventing relative movement of these two members. 80

When it is desired to grasp an article, such as the handle of a wheelbarrow, the shoulder of the wearer is lowered to bring the tips of the resilient fingers below the handle. As the wearer straightens up, the 85 entire hand is raised, bringing the resilient fingers 4 into engagement with the handle, on one side thereof, and the palm spring 6 into engagement with the other side of said handle. The fingers and palm spring are 90 thus pressed outwardly on either side of the handle, and, owing to their spring nature, they tend to grip the handle in a manner similar to a natural hand. 95

What is claimed as new, is:—

1. An artificial hand having a thumb and fingers each consisting of a frame member, a resilient palm comprising a coiled spring compressible toward the back of the hand, and a base piece in the wrist portion of said hand in which said wires and said coiled spring are anchored. 100

2. An artificial hand having fingers and a thumb each consisting of a frame member, a base piece in the wrist portion of said hand, 105 said finger frame members being anchored in said base piece and projecting from one side thereof, the said thumb wire also being anchored in said base piece and projecting from one end thereof, and a resilient palm for said hand comprising a coiled spring anchored in said base piece and projecting from the side thereof opposite to that from which the finger frame members project and extending substantially longitudinally of said hand. 110 115

3. An artificial limb comprising a hand having fingers and a thumb, said fingers and thumb each including a frame member and a covering for said member, a base in the wrist portion of said hand supporting said frame members, a forearm, and co-operating parts carried by said forearm and base for removably securing said hand to said forearm. 120

In testimony whereof, I have signed my name to this specification, in the presence 125 of two subscribing witnesses.

JOHN J. EVERSON.
